W. E. & H. J. GAYLORD.

TEMPORARY BINDER,

APPLICATION FILED AUG. 30, 1915.

1,219,721.

Patented Mar. 20, 1917.

UNITED STATES PATENT OFFICE.

WILLIS E. GAYLORD AND HENRY J. GAYLORD, OF SYRACUSE, NEW YORK.

TEMPORARY BINDER.

1,219,721.

Specification of Letters Patent. Patented Mar. 20, 1917.

Application filed August 30, 1915. Serial No. 47,977.

To all whom it may concern:

Be it known that we, WILLIS E. GAYLORD and HENRY J. GAYLORD, citizens of the United States of America, and residents of Syracuse, in the county of Onondaga, in the State of New York, have invented new and useful Improvements in Temporary Binders, of which the following, taken in connection with the accompanying drawings, is a full, clear, and exact description.

This invention relates to certain improvements in temporary binders for loose leaves, magazines, newspapers and other periodicals and is somewhat similar to that set forth in our Patent No. 1,067,019, of July 8, 1913, in that it involves the use of one or more pairs of jaws and a sliding plate having co-operative means for opening and closing the jaws as the plate is moved endwise together with suitable means for operating the plate.

The main object, however, of our present invention is to enable the jaws to be opened and closed with greater rapidity, and at the same time to reduce the weight and cost of manufacture by reducing the number and size of the parts.

In other words, we have sought to produce the same action of the jaws as in our patent referred to by means of a single plate and a relatively short adjusting screw therefor, as distinguished from double plates and wedges and long screw spindle of the patent.

Another object is to utilize the bearing for the screw as a brace between the sides of the sheet metal frame or support, thus permitting the use of comparatively light sheet metal in the formation of the support.

Other objects and uses will appear in the following description.

40 In the drawings—

Figure 1 is a perspective view of a binder embodying the features of our invention.

Fig. 2 is an inverted plan of the same binder, omitting the cap plate, a portion of the sliding plate being broken away to show the underlying parts of the jaws.

Figs. 3 and 4 are enlarged longitudinal and transverse sectional views taken, respectively, on lines 3—3, and —4—, Fig. 1.

50 Fig. 5 is a top plan of the binder showing the jaws as partly opened.

Figs. 6 and 7 are perspective views of the jaws of one pair.

As illustrated, this binder consists of a tubular case or main supporting frame com-

posed of a base section —1— and a cap section —2—, the base section —1— having its opposite edges provided with parallel lengthwise flanges —3— projecting from one side thereof and formed in their outer faces 60 near the free edges thereof with lengthwise grooves —4—.

The cap section —2— is co-incident in length with that of the base section —1— and is preferably concavo-convex in cross 65 section with its convex face outermost and its opposite longitudinal edges bent inwardly to form ribs which are slidably interlocked with the grooves —4— so that the cap section may be removed or replaced from either 70 end by sliding it upon the base section, and when in operative position is firmly locked thereto and forms therewith an intervening chamber for the reception of the jaw-operating means, presently described. 75

The flanges —3— of the base plate are spaced some distance apart and are folded inwardly a slight distance over the main body to form guide grooves —5— for receiving the opposite edges of and guiding a 80 longitudinally movable jaw-operating plate —6— which is slideable in said grooves, and are provided with separate pairs of diagonal slots —7— one pair for each pair of jaws, each slot being adapted to receive a stud or 85 pin —8— on one of the jaws, said sliding plate being also provided at one end with a head or flange —9— having a threaded aperture —10— for receiving an operating screw —11—. 90

This screw is located within the tubular case or frame and wholly within the ends thereof and is journaled near its outer end in a cross bar —12— and is held against endwise movement by pins —13— passing 95 through apertures in the screw spindle and engaging opposite faces of the cross bar —12—, the outer end of said spindle being flattened at —14— to receive a correspondingly formed key, not shown, but by which 100 the screw may be operated to shift the plate —6— longitudinally when desired.

The main body of the base plate —1— is provided with separate pairs of longitudinally elongated openings —5— therethrough for receiving corresponding pairs of jaws —16— which are similarly formed by the same die and are interchangeable, each jaw being provided with a plurality of, in this instance three, guide flanges 110

—17— disposed in the same flat plane at substantially right angles to the main body of the jaw and spaced uniform distances apart to form intervening slots —18— of 5 substantially the same width as the flanges so that the flanges of one jaw may ride freely in the slots of the companion jaw, the object of which is to form a comparatively broad bearing for each jaw and to distribute such 10 bearing approximately the entire length of such jaw.

These flanges rest upon the inner face of the main flat body of the base section —1— and the combined width of the flanges and 15 slots between them is substantially equal to the length of the opening —15— through which the jaw projects, while the main body of the jaw is of greater length than the combined width of the flanges —17— and intervening spaces —18— so as to overhang and 20 engage the portions of the base plate at opposite ends of the opening to hold the jaws against inward displacement through the openings, it being understood that the 25 flanges —17— are of sufficient length to extend transversely across the opening nearest its jaw and some distance beyond the portion of the base plate between the openings, as shown more clearly in Fig. 4.

30 The openings —15— of each pair are of the same length, but are offset longitudinally a distance corresponding to the width of one of the flanges —17—, while one end of each jaw extends beyond the adjacent flange a 35 greater distance than the opposite end beyond its adjacent flange corresponding to the width of one of the flanges so as to enable the jaws to be assembled upon the base plate directly opposite each other with their corresponding ends in the same transverse 40 planes at substantially right angles to the longitudinal center of the base plate.

The outer longitudinal edges of the jaws are bent inwardly a slight distance toward 45 each other to form gripping ribs —19— for effecting a more positive grip upon the article which may be impinged between them.

Each jaw is provided with one of the studs —8— secured to one of its flanges —17— 50 and projecting through the corresponding slot —7— in the sliding plate —6—, the inner ends of the studs being provided with heads which are of slightly greater diameter than the width of the slots —7— for engaging 55 the inner face of the plate —6— to more effectively hold the latter against inward diagonal movement while being operated to open and close the jaws by means of the screw —11—.

60 As illustrated, the studs —8— of each pair of jaws are secured to adjacent flanges —17—, one stud on the flange of one jaw and the other stud on the adjacent flange of the other jaw, which causes the studs to be 65 arranged in staggered relation and necessi-

tates a corresponding staggered relation of the adjacent slots —7—.

The slots of each pair converge in the same direction, in this instance from the screw end of the plate —6— toward the opposite end at relatively steep angles to each other approaching a right angle so as to cause a rapid movement of the jaws from one extreme position to the other by a slight movement of the plate —6— and its 75 operating screw —11—, and owing to the staggered relation of the slots of each pair, it is necessary to extend one of the slots across the end of the other slot as illustrated in Fig. 2, it being understood that these 80 slots are of sufficient length diagonally of the plate —6— to allow the jaws to be moved the full width of the openings —15—, and therefore, the jaws may be opened a distance corresponding to the combined width 85 of the openings —15— of each pair, thus permitting the instrument to be used to bind or grip any article, such as pamphlets or newspapers having a thickness or combined thickness within the range of adjustment of 90 the jaws.

In the operation of clamping an article between the jaws, said jaws are opened a sufficient distance to receive the edge of said article between them by turning the screw 95 in one direction, and thereby shifting the plate —6— endwise, whereupon the article is placed between the jaws with its edge against the outer face of the base plate —1— and the screw —11— is then turned in a reverse direction by means of a key to operate the plate —6— for closing the jaws upon 100 said article with a sufficient degree of firmness to retain the article against accidental displacement, after which the key may be 105 removed and the binder with the article clamped therein placed in position for use without liability of being withdrawn, since it is necessary to use the key to release such 110 article.

What we claim is:

1. In a loose-leaf and pamphlet binder, the combination of a tubular support having a base section and a cap section, the base section having separate sets of jaw-openings, 115 separate sets of jaws movable in said openings transversely of the base-section and provided with guide flanges slidable thereon, a plate slidable lengthwise of the base-section across and upon said flanges and provided with separate sets of diagonal slots, 120 one for each jaw, those of both sets converging in the same direction, studs on the jaws riding in their respective slots, and a single screw for operating the plate.

2. In a loose-leaf and pamphlet binder, the combination of a base plate having jaw-openings therethrough, jaws movable in said openings transversely of the plate and having laterally projecting flanges resting there- 125

on, a jaw-operating plate slidable lengthwise of the base plate across said flanges, and provided with relatively short slots disposed at an angle of more than forty-five degrees to each other, studs on the jaws riding in said slots, and means for moving the jaw-operating plate endwise and holding it in its adjusted position.

In witness whereof we have hereunto set our hands this 18th day of August, 1915.

WILLIS E. GAYLORD.
HENRY J. GAYLORD.
